SET OF CHESS PIECES

Harvey W. Kidder, Old Sleepy Hollow Road,
Pleasantville, N.Y.

Filed June 1, 1965, Ser. No. 85,525

Term of patent 14 years

(Cl. D34—5)

FIG.2

FIG.3

FIG.5

FIG.4

FIG.6

FIG.7

FIG. 1 is a front perspective view of a set of chess pieces embodying my new design and from left to right, they are, respectively (1) Pawn, (2) Castle, (3) King, (4) Knight, (5) Queen, (6) Bishop;

FIG. 2, a top plan view of the set of chess pieces embodying my new design and from left to right, they are, respectively (1) King, (2) Bishop, (3) Knight, (4) Queen; second row left to right are, respectively (1) Castle, (2) Pawn;

FIG. 3 is a rear elevation of the King embodying my new design of a set of chess pieces;

FIG. 4, a rear elevation of the Queen of the set embodying my new design;

FIG. 5, a rear elevation of the Knight of the foregoing set of chess pieces;

FIG. 6 is a rear elevation of the Pawn of my chess set; FIG. 7, a bottom view of substantially all of the pieces.

The Castle and Bishop are shown in perspective as part of FIG. 1. The rear views of these pieces are identical to the perspective views thereof illustrated in FIG. 1 as all sides of these chess pieces are identical in design.

I claim:

The ornamental design for a set of chess pieces, as shown and described.
